UNITED STATES PATENT OFFICE.

CHARLES H. PATTERSON, OF LEADER, MINNESOTA.

TRAFFIC SIGNAL.

Application filed October 24, 1923. Serial No. 670,552.

To all whom it may concern:

Be it known that CHARLES H. PATTERSON, a citizen of the United States of America, residing at Leader, in the county of Cass 5 and State of Minnesota, has invented new and useful Improvements in Traffic Signals, of which the following is a specification.

The object of the invention is to provide a simple and efficient traffic signal which may 10 be readily operated by the driver of a motor vehicle with the minimum distraction of attention and diversion of effort from the manipulation of the steering wheel of the vehicle whereby following and approaching 15 vehicles and pedestrians may be advised of the intention of the driver in the matter of changing direction of progress or of stopping or reducing the speed of movement to minimize risk of collision and confusion in 20 congested thoroughfare; and moreover to provide a device which may be applied with the minimum of preparation to any of the conventional forms of vehicles under conditions assuring the proper functioning 25 thereof; and with these objects in view the invention consists in a construction and combination of parts of which a preferred embodiment is shown in the accompanying drawings, wherein:—

30 Figure 1 is a side view, and

Figure 2 is a longitudinal sectional view of a signal embodying the invention.

Figures 3 and 4 are transverse sectional views respectively on the planes indicated 35 by the lines 3—3 and 4—4 of Figure 1.

Figure 5 is an inner end view of the device.

Figure 6 is a detail view showing the means whereby the casing is secured to the 40 bracket arm.

Figure 7 is a transverse sectional view on the plane indicated by the line 7—7 of Figure 2.

The device consists essentially of a tubular bracket arm 10 with which may be associated clamps 11 for engagement with an interposed wall or element 12 of the vehicle, a casing 13 carried by said bracket arm and provided with front and rear windows 14 45 consisting of light penetrable panels of glass or its equivalent, a signal head 15 having a tubular spindle 16 mounted in and extending through the bracket arm 10, an operating handle 17 secured to the inner end of 50 said spindle. The lighting unit 18 consist-

ing of an electric bulb or its equivalent is arranged within the head with the conductor wires 19 thereof extending through the tubular spindle and serve either by the magneto or battery or by the lighting system of 60 the vehicle.

The bracket arm is provided with a disk head 20 having the peripheral groove 21 for the reception of a bead 22 at the inner end of the casing 14, said inner end preferably 65 being split as indicated at 23 to permit it to expand and contract, and a locking ring 24 is fitted in the bead for contraction by the shackle 25 to lock the casing to the disk head while permitting removal thereof with 70 facility when access to the interior of the signal is desired.

The signal head consists of a plurality of panels preferably having duplicates arranged in diametrically opposite positions 75 and with the several interchangeable panels respectively designated and covered or distinguished in such a way as to attract attention for respective or selective display through the panels of the casing so that by 80 turning the spindle it may be possible to display forwardly and rearwardly a signal indicating the intention of the operator to turn to the right or left according to the direction in which the arrow points, or the word "Stop" or its equivalent to indicate 85 the intention of the driver to check or reduce or terminate the forward motion of the vehicle. In the construction illustrated this signal head of which the panels are light 90 penetrable to permit the light of the lamp or signal unit to shine therethrough and display the coloring thereof as well as such words or emblems as may appear thereon, is of cylindrical form and is threaded at its inner end as indicated at 26 into the hub of a disk 27 at the adjacent end of the tubular spindle so that the detachment thereof may 95 be effected when required for repair or replacement.

The handle or operating element 17 is an integral radial projection of the disk 27 and the hub of the latter is provided with a spring-actuated pawl 29 engaging the teeth 30 on the extremity of the tubular bracket arm 10 but these teeth are channeled so as to permit the pawl to snap from one to the other as the handle is being actuated, so that there may be maintained any desired adjustment against displacement by 110

the vibration of the car or vehicle while permitting of adjustment without objectionable effort on the part of the operator.

It will further be understood that where as the operating means herein represented as the handle 17 may be directly manipulated by the operator if the signalling device is located in such a position as to be readily reached, other suitable or conventional means for communicating motion thereto may be employed where it is desirable to locate the signal at a point more or less remote from the driver's seat.

Having described the invention, what is claimed as new and useful is:—

1. A traffic signal having a casing provided with light penetrable panels, a tubular bracket arm for supporting the casing and having means for attachment to a vehicle, a revolute signal head mounted within the casing and having a spindle mounted in said bracket arm, the signal head being provided with panels for selective arrangement in registration with the panels of the casing, and means for turning the signal head, the

bracket arm being provided at its outer end with a disk head, and the casing having a split inner end fitted upon said disk head and having an interlocking engagement therewith.

2. A traffic signal having a casing provided with light penetrable panels, a tubular bracket arm for supporting the casing and having means for attachment to a vehicle, a revolute signal head mounted within the casing and having a spindle enclosed by said bracket arm, the signal being provided with panels for selective arrangement in registration with the panels of the casing, a disk having a radial actuating handle and a hub fitted upon the extremity of said spindle, and a spring-actuated pawl carried by the hub of said disk, that end of the bracket arm remote from the casing being provided with teeth with which said pawl engages to maintain the angular position of the spindle after operation by said handle.

In testimony whereof he affixes his signature.

CHARLES H. PATTERSON.
